CLAIM

I claim the ornamental design for a board game, as shown and described.

DESCRIPTION

FIG. 1 is a perspective view of a board game of my design. FIG. 2 is a front elevation view thereof; FIG. 3 is a rear view thereof; FIG. 4 is a side elevation view thereof; FIG. 5 is an opposite side elevation view thereof; FIG. 6 is a top view of the board game of FIG. 1; and, FIG. 7 is a bottom view of the board game of FIG. 1.

1 Claim, 7 Drawing Sheets
